UNITED STATES PATENT OFFICE.

PETER SOLAINI, OF NEW YORK, N. Y.

LOCK.

1,224,228.

Specification of Letters Patent.

Patented May 1, 1917.

Application filed December 27, 1916. Serial No. 139,137.

To all whom it may concern:

Be it known that I, PETER SOLAINI, a subject of the King of Italy, residing at New York city, county and State of New York, have invented a new and useful Lock, of which the following is a specification.

My invention relates to improvements in locks and in the particular form shown I have combined both a locking bolt and a latch bolt, the same being arranged in a novel manner as hereinafter set forth.

In the accompanying drawings:

Figure 1 shows the invention as applied to the inside of a door and door casing, certain parts being removed to show the interior arrangement, said view being partly in section on the line 1—1 of Fig. 5.

Fig. 2 is a view of the reverse side of certain parts shown in Fig. 1, said parts being in a different position and partly in section on the line 2—2 of Fig. 5.

Fig. 3 is a view similar to Fig. 1, with certain parts removed, the parts illustrated being shown in a different position.

Fig. 4 is an edge view of the door with the lock thereon.

Fig. 5 is a section on the line 5—5 of Fig. 1.

Fig. 6 is a detail view.

1 represents a door. 2 represents a casing. 3 represents the lock case. 4 represents the casing of what I may term the strike or keeper. 5 represents a locking bolt which is pivoted within the casing 3 and which has a curved end 5^a which operates as the bolt proper. 6—6 are fixed abutments within the keeper housing 4. When the lock bolt is turned to the position shown in Fig. 3, the door is unlocked. When, however, the lock bolt is turned to the position shown in Fig. 1, the door is locked, the bolt end 5^a being swung around so as to project into the keeper and around the abutments 6—6. The end of the bolt 5^a is by preference sufficiently long so that it will project back into a cavity in the lock casing 3 as shown in Fig. 1 when the door is locked thereby adding greatly to security. Obviously this bolt is effective when applied either to a swinging door or a sliding door.

When applied to a swinging door the lock may also be provided with a latch bolt 7, which is suitably mounted in the lock casing 3. In this instance the latch bolt 7 is mounted to reciprocate and is normally pro-

jected by springs 8—8. 9 is a finger piece at the back of the lock casing which is connected by a stem 10 to the rear end of the latch bolt 7 so that the latch bolt may be retracted by pulling back the finger piece 9 to the dotted line position shown in Fig. 2. 11 is a knob at the inner side of the lock case 3, the same being directly connected in any suitable manner to the swinging dead bolt 5, so that when the knob is turned the 60 said dead bolt will be correspondingly turned to the locked or the unlocked position. This knob 11 has a tubular shank 12. Projecting into the opposite end of the tubular shank 12 is a stem 14 which is mounted at the inner end of the usual plug portion 15 of a pin cylinder lock, whereby when the plug 15 is turned the stem 14 will correspondingly turn. The stem 14 may be 65 yieldingly mounted on the end of the plug 15 so that it may enter the sleeve 12 without binding. The inner end of the sleeve 12 is cut away at one side as best seen in Figs. 2 and 5. 16 is a pin carried by the stem 14 and standing in the cut away portion of the 70 sleeve 12, the cut away portion being sufficient to permit the stem 14 to be turned 75 freely to a limited extent without turning the sleeve 12, for the purpose hereinafter described. The stem 14 may have a series 80 of holes to receive the pin 16 so that the lock may be applied to doors of different thicknesses, the cylinder lock being made suitably adjustable. If the door were thicker than 85 that indicated in Fig. 5, the cylinder lock 90 would be adjusted thereto and the pin 16 would be screwed into the proper hole in the stem 14 so as to position the pin 16 in the 95 cut away portion of the sleeve 12. 17 is a roll back mounted on the sleeve 12. This 100 roll back faces up with a shoulder 18 on the tail of the latch. 19 is a spring that may be located in the lower part of the casing 3 and which may frictionally engage a shoulder 5^b on the hooked arm 5^a of the dead bolt in its retracted position, (see Fig. 2) and which 105 may also frictionally engage another shoulder 5^c on the dead bolt to frictionally hold the dead bolt in its projected position shown in Fig. 1.

Operation: Assuming the parts stand in the position shown in Fig. 2, the latch bolt 7 may now be retracted either by turning the knob 11 in direction to throw the roll back 17 against the shoulder 18, or by pull-

105

110

ing back on the finger piece 9. If the parts stand in this position the latch may be retracted by a suitable key by simply introducing the same into the cylinder lock and 5 turning the stem 14 so as to swing the pin 16 in a counterclockwise direction (when viewed as in Fig. 2) until said pin strikes against the shoulder at the other side of the clearance slot or cut away portion of 10 the sleeve 12, whereupon a continued movement of the key in the same direction will swing the roll back 17 against the shoulder 18 and retract the latch bolt 7.

Now assuming that it is desired to lock 15 the door. Starting with the parts shown in the position indicated in Fig. 2, the dead bolt 5 may be advanced either by turning the knob 11 directly by hand (as viewed in Fig. 2) so as to swing the bolt end 5^a into 20 the locking position indicated in Fig. 1; or, the said knob and dead bolt 5 may be turned by a suitable key which may be inserted from the outside to turn the stem 14 and to thereby indirectly engage and turn 25 the knob 11 and bolt 5 for the aforesaid purpose.

Now assuming it is desired to enter from 30 the outside when the door is locked and latched, as shown in Fig. 1. A suitable key is introduced into the plug 15 of the cylinder lock when the same is turned in a clockwise direction (as viewed in Fig. 1). This turning movement first turns the knob so as to swing back the bolt 5 from the position 35 indicated in Fig. 1 to that indicated in Fig. 2. By continuing to turn the key the bolt 5 continues to swing back to the position shown in Fig. 3, and simultaneously the roll back 17 engages the shoulder 18 and 40 retracts the latch. When the door is dead locked from the outside by means of a key, the clearance notch in the inner end of the hollow sleeve 12 permits the plug 15 to be turned back part of a revolution 45 after the bolt is projected so that the said key will line up the usual tumblers and followers of the cylinder lock whereby the key may be removed. Otherwise, of course, the key could not be removed.

50 Obviously, if a door has been locked from the outside, the following steps would be taken to open the door from the inside: First, the knob 11 would be turned to retract the dead bolt 5, then the latch bolt would be 55 retracted by finger engagement with the finger piece 9.

What I claim is:

1. In a lock of the character described, a casing, a keeper having an abutment, a dead bolt pivotally carried by the casing and having a hooked end adapted to be swung outwardly around said keeper abutment, the extreme end of said dead bolt again entering said casing when in the 65 final locking position, and a spring latch

bolt carried by said casing and arranged to engage said keeper, and means for independently operating said dead bolt and latch bolt from the inner side of the lock, and means at the outer side of the lock for 70 operating both the latch bolt and the dead bolt, said outside operating means being key controlled, with a connection between said key controlled means and one of the operating means at the inner side of the 75 lock, said connection permitting a limited degree of rotary movement of the key without actuating the inside operating means.

2. In a lock of the character described, a casing, a keeper having an abutment, a dead bolt pivotally carried by the casing and having a hooked end adapted to be swung outwardly around the keeper abutment, a spring pressed latch bolt carried by the casing, and a single operating knob for both 85 the hooked dead bolt and the spring pressed latch bolt.

3. In a lock of the character described, a casing, a keeper having an abutment, a dead bolt pivotally carried by the casing and 90 having a hooked end adapted to be swung outwardly around the keeper abutment, a spring pressed latch bolt carried by the casing, an operating knob connected with the hooked dead bolt and a lost-motion connection between the operating knob and the 95 spring pressed latch bolt.

4. In a lock of the character described, a casing, a keeper having an abutment, a dead bolt pivotally carried by the casing and 100 having a hooked end adapted to be swung outwardly around the keeper abutment, a spring pressed latch bolt carried by the casing, an operating knob operatively connected with both the hooked dead bolt and 105 the spring pressed latch bolt and a cylinder lock operatively connected with the hooked dead bolt and spring pressed latch bolt.

5. In a lock of the character described, a casing, an operating knob having a tubular shank journaled in said casing, a dead bolt mounted on the tubular shank of said knob and adapted to be projected by the rotation of said knob, a cam on the tubular shank and a latch bolt operated by said cam. 110

6. In a lock of the character described, a casing, an operating knob having a tubular shank journaled in said casing, a dead bolt mounted on the tubular shank of said knob and adapted to be projected by the rotation 115 of said knob, a cam on the tubular shank and a latch bolt operated by said cam, and a cylinder lock having an operating member engaging the tubular shank of the operating knob.

7. In a lock of the character described, a casing, a spindle journaled in the casing, a dead bolt mounted on said spindle, a knob at one side of the casing for turning the dead bolt spindle, a cylinder lock on the 120

opposite side of the casing having a lost-motion connection with the dead bolt spindle, a spring pressed latch bolt in the casing and means on the dead bolt spindle for operating said latch bolt.

8. In a lock of the character described, a casing, a spindle journaled in the casing, a dead bolt mounted on said spindle, a knob at one side of the casing for turning the dead bolt spindle, a cylinder lock on the opposite side of the casing having a lost-motion connection with the dead bolt spindle, a spring pressed latch bolt in the casing and means on the dead bolt spindle for operating said latch bolt, and a pull back finger piece connected to the latch bolt for

retracting the latch bolt independently of the operation of the operating knob.

9. In a lock of the character described, a casing, a tubular spindle journaled in said casing and having its inner end cut away at one side, an operating knob connected with the outer end of said tubular spindle, a hooked dead bolt mounted on the tubular spindle, a latch bolt in the casing, a cam on the tubular spindle for operating the latch bolt, a cylinder lock having a stem engaged in the tubular spindle and a lug on said stem standing in the cut away portion in the end of the tubular spindle.

PETER SOLAINI.
